United States Patent Office

Des. 180,742
Patented Aug. 6, 1957

180,742

RADIO CABINET

John W. Mason, Detroit, Mich., assignor to Admiral Corporation, Chicago, Ill., a corporation of Delaware

Application December 18, 1956, Serial No. 44,244

Term of patent 14 years

(Cl. D56—4)

Fig. 1.

Fig. 2.

Fig. 3.

Fig. 1 is a front perspective view of a radio cabinet, showing my new design;

Fig. 2 is a right end elevational view thereof, partly in section; and

Fig. 3 is a fragmentary rear elevational view thereof. I claim:

The ornamental design for a radio cabinet, as shown.
